CLAIM

The ornamental design for a nozzle for cartridge inserted in a fluid emitting device, as shown and described.

DESCRIPTION

FIG. 1 is a front, left side, top perspective view of a nozzle for cartridge inserted in a fluid emitting device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, right side, top perspective view thereof;

FIG. 9 is a reference perspective view thereof, showing a state in which this article is used; and,

FIG. 10 is another reference perspective view thereof, showing a state in which this article is used.

The evenly broken lines are shown for the purpose of illustrating both parts of the article as well as environmental subject matter. The dot-dash lines represent the boundaries of the claim. None of the broken lines form part of the claimed design.
